UNITED STATES PATENT OFFICE.

DAVID D. TRACY, OF JACKSON, MICHIGAN.

CONDUIT MOLD.

Application filed June 7, 1926. Serial No. 114,171.

This application is a continuation in part of my application for Letters Patent, filed Nov. 2, 1925, Ser. #66,806.

The main objects of this invention are:

5 First, to provide an improved conduit mold which is well adapted for use in the manufacture of conduits of large dimensions for sewers, water conduits and other purposes.

10 Second, to provide an improved conduit mold which is capable of very rapid manipulation.

Third, to provide an improved conduit mold which can be readily set up or knocked 15 down without liability of injuring the molded section.

Objects relating to details and economies of construction and operation of my invention will definitely appear from the detailed 20 description to follow. The invention is clearly defined and pointed out in the claims.

A structure embodying the features of my invention is clearly illustrated in the accompanying drawing forming a part of this 25 application, in which:

Fig. 1 is a side elevation of my improved conduit mold.

Fig. 2 is a plan view thereof.

Fig. 3 is a fragmentary vertical section 30 on a line corresponding to line 3—3 of Fig. 2 with the mold filled.

Fig. 4 is a plan view of the base of the mold.

Fig. 5 is a fragmentary section on a line 35 corresponding to line 5—5 of Figs. 2 and 4.

Fig. 6 is a fragmentary section on a line corresponding to line 6—6 of Figs. 2 and 4.

Fig. 7 is a fragmentary elevation of the inner wall.

40 Fig. 8 is a plan view of the top ring of the form or mold.

Fig. 9 is a fragmentary inside view of the inner wall with the top ring in position.

Fig. 10 is a fragmentary side elevation 45 with the latch in disengaged position.

Fig. 11 is a detail vertical section on a line corresponding to line 11—11 of Figs. 10 and 12 showing further details of the latch.

Fig. 12 is a detail horizontal section on a 50 line corresponding to line 12—12 of Fig. 11.

Fig. 13 is a detail section corresponding to that of Fig. 12 with the latch disengaged.

Referring to the drawing, the base 1 is provided with an outer annular shoulder 2 and an inner annular shoulder 3, the inner shoulder having a positioning lug 4 pro-

jecting therefrom, the shoulders having pins 5 projecting from their faces. The base, between these shoulders, is suitably conformed to shape or form the ends of the conduit section, the base in the structure illustrated having an outer segmental rib-like portion 25 and an inner segmental portion 26 arranged with the ends in overlapping relation as shown. These portions are adapted to form the end of the conduit with inner and external recesses adapted to receive calking material when the end of the conduit section is placed in abutting relation to a coacting conduit section.

The inner form wall is made up of three complementary longitudinal sections 6 having joint bars 7 secured at one edge thereof so as to project into overlapping relation with the coacting edge of the adjacent section, thus forming a closed joint when the parts are secured together. These joint bars 7 are preferably formed of angle iron with their angles facing inwardly, the inwardly projecting arms 8 having slots 9 therein to receive the latches 10 which are pivoted at 11 on the reinforce bars 12 to project through the slots. The reinforce bars 12 are secured in spaced relation to the underlapping edges of the sections and are provided with keepers 12' to receive the latches. This provides a means for quickly securing the sections together and a means which can be readily released even when the form is filled. The sections are also very rigidly supported in position. One of the inner wall sections has a notch 13 in the bottom thereof coacting with the positioning lug 4.

The outer wall comprises complementary sections 14 having joint bars 7 and reinforce bars 12 corresponding to the joint and reinforce bars of the inner wall sections. The wall sections have holes 15 therein to receive the pins 5, thus detachably securing the walls to the base.

A top ring 16 is provided, fitting within the inner wall section, the bars 7 and 12 being spaced at their upper ends from the upper ends of the walls to receive this ring. The ring has hooks 17 thereon engaging the joint bars 7 for detachably securing the ring in place.

The inner wall sections have notches 18 in their upper edges adapted to receive the radial projecting arms 19 of the ring which constitute spacing members for the upper ends of the mold walls.

The base 1 has sockets 20 therein adapted to receive the lower ends of the reinforce and tie bars 21, while the arms 19 have sockets 22 therein alined with these sockets 20 to receive the upper ends of the bars 21.

In the embodiment illustrated, the foraminated reinforcing elements 23 are supported by these bars 21, the upper ends of the elements 23 being further supported by the 10 spacing blocks 24 which are notched on their under edges to receive the reinforcing element.

By thus arranging the parts, I provide a mold which may be very quickly set up or 15 knocked down, is well adapted for the molding of large conduits and can be easily removed without likelihood of injuring the conduit.

By engaging the wall sections with the 20 pins 5 and securing the top ring by means of the hooks, the parts are effectively secured together so that the weight of the cement and tamping and jarring to which it is subjected in molding does not separate the 25 parts. At the same time, they may be quickly separated when it is desired to knock down the mold.

I have illustrated and described my improvements in an embodiment which I regard as very practical. I have not attempted to illustrate or describe certain modifications or adaptations as I believe the disclosure made will enable those skilled in the art to embody or adapt my improvements as may 35 be desired.

Having thus described my invention what I claim as new and desire to secure by Letters Patent, is:

1. In a mold for conduits, the combination 40 of a base member having inner and outer form wall supports, an inner wall positioning lug and wall engaging pins thereon, said base having reinforce sockets therein, inner and outer form walls, each comprising a plurality of longitudinal complementary sections provided with joint bars disposed to project beyond one edge of the sections in overlapping relation to the edges of the adjacent sections, said sections being 45 also provided with longitudinal reinforcing bars spaced from their overlapping edges, one of the inner wall sections being notched at its lower end to engage said positioning lug on said base, wall sections having holes 50 to receive said pins, hooks pivotally mounted on said reinforcing bars to engage said joint bars whereby the sections are detachably secured together, a supporting ring engaging the upper end of said inner wall and having 55 radial arms constituting spacing members for the outer wall, said arms having reinforce sockets alined with said reinforce sockets in said base, and hooks on said ring detachably connecting the same with said joint 60 bars.

2. In a mold for conduits, the combination 70 of a base member having inner and outer form wall supports, inner and outer form walls, each comprising a plurality of longitudinal complementary sections provided with joint bars disposed to project beyond one edge of the sections in overlapping relation to the edges of the adjacent sections, said sections being also provided with longitudinal reinforcing bars spaced from their overlapping edges, the inner wall sections having notches in their upper ends, hooks 75 pivotally mounted on said reinforcing bars to engage said joint bars whereby the sections are detachably secured together, a supporting ring engaging the upper end of said inner wall and having radial arms engaging said notches therein and constituting spacing members for the outer wall, and hooks on said ring detachably connecting the same with said joint bars.

3. In a mold for conduits, the combination 80 of a base member having inner and outer form wall supports, inner and outer form walls, each comprising a plurality of longitudinal complementary sections provided with joint bars disposed to project beyond one edge of the sections in overlapping relation to the edges of the adjacent sections, said sections being also provided with longitudinal reinforcing bars spaced from their overlapping edges, hooks pivotally mounted on said reinforcing bars to engage said joint bars whereby the sections are detachably secured together, a supporting ring engaging the upper end of said inner wall and having radial arms 85 constituting spacing members for the outer wall, and hooks on said ring detachably connecting the same with said joint bars.

4. In a mold for conduits, the combination 90 of a base member adapted to receive inner and outer form walls and having an inner wall positioning lug, said base having reinforce sockets therein, inner and outer walls comprising longitudinal complementary sections 95 detachably connected together, the inner wall having a notch in its lower end to engage said positioning lug and notches in its upper end, a supporting ring engaging the inner wall and having radial arms constituting spacing members for the outer wall, said arms having reinforce sockets therein aligned with said reinforce sockets in said base, and means for detachably connecting 100 said ring with said inner wall.

5. In a mold for conduits, the combination 105 of a base member adapted to receive inner and outer form walls and having an inner wall positioning lug, said base having reinforce sockets therein, inner and outer walls comprising longitudinal complementary sections 110 detachably connected together, the inner wall having a notch in its lower end to engage said positioning lug and notches in 115

- its upper end, and a supporting ring engaging the inner wall and having radial arms constituting spacing members for the outer wall, said arms having reinforce sockets therein alined with said reinforce sockets in said base.
6. In a mold for conduits, the combination of a base member adapted to receive inner and outer form walls and having an inner wall 10 positioning lug and wall engaging pins, inner and outer walls comprising longitudinal complementary sections detachably connected together, the walls having holes to engage said pins, the inner wall having a notch in its lower end to engage said positioning lug, a supporting ring engaging the inner wall and having radial arms constituting spacing members for the outer wall, and means for detachably connecting said 15 ring with said inner wall.
7. In a mold for conduits, the combination of a base member adapted to receive inner and outer form walls and having an inner wall positioning lug, inner and outer walls comprising longitudinal complementary sections detachably connected together, the inner wall having a notch in its lower end to engage said positioning lug, and a supporting ring engaging the inner wall and having 20 radial arms constituting spacing members for the outer wall.
8. In a mold for conduits, the combination of a base member having inner and outer form wall supporting shoulders thereon, the inner shoulder having a positioning lug projecting therefrom, the base having a projecting pin thereon, inner and outer form walls each comprising a plurality of longitudinal complementary sections, one of the wall sections having a hole to receive said pin, and one of the inner wall sections being notched to engage said lug, means for detachably connecting said sections to each other, and a spacing ring detachably connected to the 25 inner wall.
9. In a mold for conduits, the combination of a base member having inner and outer form wall supporting shoulders thereon, the inner shoulder having a positioning lug projecting therefrom, one of the shoulders having projecting pins thereon, inner and outer form walls each comprising a plurality of longitudinal complementary sections, one of the wall sections having a hole to receive said pin, and one of the inner wall sections being notched to engage said lug, and means for detachably connecting said sections to each other.
10. In a mold for conduits, the combination of a base member adapted to receive inner and outer form walls, inner and outer walls comprising complementary sections detachably connected together, the inner wall having notches in its upper end, and a 30 supporting ring fitting within the inner wall and having radial arms engaging said notches therein constituting spacing members for the outer wall.
11. In a mold for conduits, the combination of a base member adapted to receive inner and outer form walls, inner and outer walls comprising longitudinal complementary sections detachably connected together, a supporting ring engaging the inner wall and having radial arms constituting spacing members for the outer wall, said base member and arms having alined reinforce sockets.
12. In a mold for conduits, the combination of a base adapted as a form wall support, a wall comprising a plurality of longitudinal complementary segmental sections provided with angle iron joint bars disposed to project beyond one edge of the sections in overlapping relation to the edges of the adjacent sections, said sections being also provided with longitudinal reinforcing bars spaced from their overlapping edges, the projecting angles of said joint bars being slotted, and latches pivotally mounted on said joint bars to swing in said slots in the projecting angles thereof, said reinforce bars being provided with upwardly facing keepers with which said latches are engageable.
13. In a mold for conduits, the combination of a base adapted as a form wall support, a wall comprising a plurality of longitudinal complementary segmental sections provided with angle iron joint bars disposed to project beyond one edge of the sections in overlapping relation to the edges of the adjacent sections, the projecting angles of said joint bars being slotted, and latches pivotally mounted on said joint bars to swing in said slots in the projecting angles thereof, said reinforce bars being provided with upwardly facing keepers with which said latches are engageable.
14. In a mold for conduits, the combination of a base adapted as a form wall support, a wall comprising a plurality of longitudinal complementary sections provided with joint bars disposed to project beyond one edge of the sections in overlapping relation to the edges of the adjacent section, said sections being also provided with longitudinal reinforce bars spaced from their overlapping edges, the outwardly projecting angles of the joint bars being slotted, latches pivotally mounted on said joint bars to swing in said slots thereof, the walls of the slots constituting supports for said latches, and coacting upwardly facing hook-like keepers on said reinforcing bars, the latches being provided with lugs adapted to engage the ends thereof.
15. In a mold for conduits, the combination of a base member, inner and outer form walls detachably mounted thereon and each comprising a plurality of longitudinal complementary sections provided with joint

bars disposed to project beyond one edge of the sections in overlapping relation to the edges of the adjacent sections, the inner wall sections having notches in their upper ends, 5 and a supporting ring fitting within the upper end of said inner wall and having radial arms engaging said notches therein and constituting spacing members for the outer wall.

16. In a mold for conduits, the combination of a base member, inner and outer form walls detachably mounted thereon and

each comprising a plurality of longitudinal complementary sections provided with joint bars disposed to project beyond one edge of the sections in overlapping relation to the 15 edges of the adjacent sections, and a supporting ring engaging the upper end of said inner wall and having radial arms constituting spacing members for the outer wall.

In witness whereof I have hereunto set 20
my hand.

DAVID D. TRACY.
